US00D899529S

(12) **United States Design Patent** (10) **Patent No.:** **US D899,529 S**
Chen (45) **Date of Patent:** **** Oct. 20, 2020**

(54) **CONTROLLER**

(71) Applicant: **SZ DJI Technology Co., Ltd.**,
Shenzhen (CN)

(72) Inventor: **Yiwei Chen**, Shenzhen (CN)

(73) Assignee: **SZ DJI Technology Co., Ltd.**,
Shenzhen (CN)

(**) Term: **15 Years**

(21) Appl. No.: **29/709,652**

(22) Filed: **Oct. 16, 2019**

Related U.S. Application Data

(63) Continuation of application No. 29/657,351, filed on Jul. 20, 2018.

(51) **LOC (12) Cl.** **21-01**

(52) **U.S. Cl.**

USPC **D21/566**

(58) **Field of Classification Search**

USPC D13/168; D14/195, 218; D21/333, 561,
D21/566; D12/174, 345

CPC A63F 13/06; A63H 30/04; G08C 17/02;
G08C 23/04

See application file for complete search history.

(57) **CLAIM**

The ornamental design for a controller, as shown and described.

DESCRIPTION

FIG. 1 is a top front perspective view of a controller showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the controller that form no part of the claimed design.

The dot-dash broken lines in the figures show boundaries that form no part of the claimed design.

1 Claim, 6 Drawing Sheets
